STOCKING

William M. Langer, Berlin, N. J.

Application June 29, 1949, Serial No. 3,628

Term of patent 7 years

(Cl. D47—7)

To all whom it may concern:

Be it known that I, William M. Langer, a citizen of the United States, residing in Berlin, in the county of Camden and State of New Jersey, have invented a new, original, and ornamental Design for a Stocking, of which the following is a specification, reference being had to the accompanying drawing, forming part thereof.

In the drawing, Fig. 1 is a fragmentary perspective view of a stocking embodying my new design; Fig. 2 is a side elevational view of a stocking embodying my new design; Fig. 3 is a fragmentary rear elevational view embodying my new design; and Fig. 4 is an enlarged fragmentary view embodying my new design.

I claim:

The ornamental design for a stocking, as shown.

WILLIAM M. LANGER.
